UNITED STATES PATENT OFFICE.

CHARLES C. BADEAU, OF SCHENECTADY, NEW YORK, ASSIGNOR TO GENERAL ELECTRIC COMPANY, A CORPORATION OF NEW YORK.

CIRCUIT-BREAKER.

SPECIFICATION forming part of Letters Patent No. 695,134, dated March 11, 1902.

Application filed July 25, 1901. Serial No. 69,647. (No model.)

To all whom it may concern:

Be it known that I, CHARLES C. BADEAU, a citizen of the United States, residing at Schenectady, county of Schenectady, State of New York, have invented certain new and useful Improvements in Circuit-Breakers, (Case No. 2,205,) of which the following is a specification.

This invention relates to automatic circuit-breakers, the object being to render more sensitive the tripping mechanism and to counterbalance the effects of friction and other causes which contribute to an uncertainty of the tripping-point of the circuit-breaker.

15 In carrying out the invention I provide the tripping-armature with an auxiliary magnetic field of sufficient density to overcome the friction of the moving parts and counterbalance the normal tension of the calibrating-spring, 20 by which I render the armature free to obey a smaller excess of current than where these opposing tendencies must be overcome by the load-current. Thus the device will be free to respond at a definite load-current, the preliminary strain of the calibrating-spring being counteracted and a greater aggregate field density provided for the trip-armature.

The novel features of my invention will be more particularly hereinafter described, and 30 will be definitely indicated in the claims appended to this specification.

In the accompanying drawings, which illustrate the invention, Figure 1 is a sectional view showing a tripping-armature of an automatic circuit-breaker and its calibrating-spring and the auxiliary magnet opposing the tension of the spring. Fig. 2 is a side elevation of a known type of circuit-breaker to which the improvements have been added.

40 Referring, first, to Fig. 1, 1 represents an electromagnet which may be permanently excited by a shunt-circuit or by an independent source of current, the core and pole-pieces 2 2^a of which maintain a continuous field of force acting upon a trip-armature 3. It is not absolutely essential that this continuous field of force should be furnished by an electromagnet, as a permanent magnet might in some cases be employed. To the trip-armature 45 is connected through a lever a retracting device, such as a spring 4, adjusted by a

screw 5, so as to determine the calibration of the circuit-breaker. The particular type of tripping device shown is one adapted for currents of very heavy amperage, to which the invention is particularly well adapted. In this type the field of force of the circuit-breaker terminal itself is relied upon to trip the circuit-breaker. The end of this stud is seen at 6, Fig. 1. The pole-pieces 2 2^a overlap the sides of this terminal or stud and have magnetism induced by the field of force of the heavy current passing through the stud when the circuit is closed. Thus the friction of the parts and the initial tension of the calibrating-spring is compensated by the auxiliary magnet, and the only work to be performed by the current passing through the circuit governed by the circuit-breaker is the additional strain imposed on the spring to trip the mechanism, thus insuring greater precision of operation at a definite load-current. Moreover, the extra field of force furnished creates a greater aggregate magnetic density and adds greatly to the tripping power of the current passing through the breaker, since the interfering effects of friction in the toggles and the increasing tension of the spring are less effective with the increased magnetic density.

80 In Fig. 2 the device is shown as applied to a modern type of automatic circuit-breaker of large capacity, in which 7 represents a heavy bridging-contact normally completing the circuit and 8 a shunt-contact through which the final break is made. 9 is a lever pivoted to the frame and loosely connected to the trip-armature 3, which when operated strikes a pin 10 and knocks down a toggle which releases the circuit-breaker. These parts are 90 shown merely by way of example, as they form no part of my present invention. 6 6^a represent the studs or terminals which connect through the rear of a supporting-board 11 with the control-circuit.

95 What I claim as new, and desire to secure by Letters Patent of the United States, is—

1. In combination with a circuit-breaker and its magnetic tripping devices, an auxiliary device to overcome the initial tension of the retractile agent for the trip-armature.
2. In an automatic circuit-breaker, the com-

bination of magnetic tripping devices, a retractile agent, and an auxiliary magnet for increasing the density of the tripping field of force.

5. 3. In an automatic circuit-breaker, the combination with magnetic tripping devices, of a separately-excited auxiliary magnet acting attractively upon the armature to assist the magnetic tripping devices.
10. 4. In an automatic circuit-breaker, tripping devices controlled by a magnetic circuit embracing the circuit-breaker terminal, and an auxiliary magnet normally furnishing a definite magnetizing force to said tripping magnet.
15. 5. An automatic circuit-breaker provided with a magnetic yoke around a circuit-ter-

minal, an armature acting through an air-gap in said yoke, and a separately-excited coil normally furnishing a definite degree of assisting magnetizing force acting co-operatively with the current through the stud on the tripping devices.

6. An automatic circuit-breaker provided with setting devices, magnetic tripping devices, and an auxiliary magnet acting to overcome the friction of the moving parts.

In witness whereof I have hereunto set my hand this 23d day of July, 1901.

CHARLES C. BADEAU.
